US0D1090522S

(12) **United States Design Patent** (10) **Patent No.:** **US D1,090,522 S**
(45) **Date of Patent:** **** Aug. 26, 2025**

(54) **MOBILE PHONE HOLDER**

(71) Applicant: **Shenzhen QiAo Communication Technology Co., Ltd.**, Shenzhen (CN)

(72) Inventor: **Hongping Huang**, Shenzhen (CN)

(73) Assignee: **Shenzhen QiAo Communication Technology Co., Ltd.**, Shenzhen (CN)

(**) Term: **15 Years**

(21) Appl. No.: **29/995,528**

(22) Filed: **Mar. 27, 2025**

(51) **LOC (15) Cl.** **14-03**

(52) **U.S. Cl.**

USPC **D14/253**

(58) **Field of Classification Search**
